ASSIGNORS TO JOHN W. LADD COMPANY, OF DETROIT, MICHIGAN, A CORPORATION
OF MICHIGAN.

BOTTLE-WASHING MACHINE.

Application filed March 18, 1927. Serial No. 176,350.

This invention relates to bottle washing machines particularly adapted for washing and sterilizing milk bottles.

One of the particular objects of the invention is to provide a machine for washing and sterilizing milk bottles in which the manual opening and closing of the valves by the operator is unnecessary.

Another object of the invention is to provide a machine of the character described in which the only manual operation necessary is the positioning of the cases containing the milk bottles in the machine and the removal of the cases after the bottles have 15 been washed and sterilized.

A further object of the invention is to provide a bottle washing machine in which the positioning of the case containing the bottles in the machine operates the necessary 20 valves for washing and sterilizing the bottles and the withdrawal of the case from the machine prepares the machine for the succeeding washing and sterilizing operation.

Another object of the invention is to provide a bottle washing machine in which the bottles are first washed in a mixture of water and steam and are finally sterilized with saturated steam.

These objects and the several novel features of the invention are hereinafter more fully described and claimed, and the preferred form of construction by which these objects are attained is shown in the accompanying drawings in which—

Fig. 1 is a section through a portion of a bottle washing machine before the bottle case is inserted therein.

Fig. 2 is a similar section through the machine after the bottle case has been inserted therein.

Fig. 3 is a section through the entire machine showing the bottle case partially inserted therein.

Fig. 4 is a section taken on line 4—4 of Fig. 3.

The machine comprises a table 1 supported on the frame members 2 as shown in Fig. 3 and this table is provided with tracks 3 on which the bottle cases 4 may be moved into the hood 5 which is positioned over the tracks 3. The cases 4 are open at the top

and bottom and the bottles 6 are supported therein on the wire racks 7. By providing the tracks 3 on which the cases may be moved into the hood with the bottles in the inverted position the entire bottom of the case is left open over the spray head 8. This spray head 8 is provided with a number of jets 9 shown in Figs. 3 and 4 which are positioned directly beneath the bottles 6 when the bottles are in the position shown in Fig. 2. As shown in Fig. 2 a steam pipe 10 is provided having a valve 11 therein. When the valve 11 is opened the steam flows through the pipe 10 and through the ejector 12. Two tanks are provided, a lower tank 13 and an upper tank 14. When the tank 13 is full of water, as shown in Fig. 1, the water fills the ejector 12 and the steam passing from the jet 15 to the venturi 16 carries water through the venturi from the ejector housing and this water and steam mixture passes upwardly through the pipe 17 and through the jets 9 in the spray head 8 and is sprayed into the bottles 6 as will be understood from Fig. 2. A small pipe 18 discharges cold water into the body of the ejector 12 in a small steady stream from a suitable source of water supply. This cold water aids in the operation of the ejector 18 and is carried into the pipe 17 with the water from the tank 13. The steam and water mixture is sprayed up into the bottles as shown in Fig. 2 and the water falls back into the upper tank 14. The upper tank 14 discharges into the lower tank 13 through an outlet 19 adapted to be closed by a weighted valve 20. A rod 21 is provided having a hook end 22 which is connected to the valve 20 and the rod 21 at the upper end extends 85 through an arm 23 and is provided with a nut 24 on the upper end thereof preventing withdrawal of the rod 21 from the arm 22. The arm 23 is secured to a rotatable horizontal rod or shaft 25 and an actuating arm 26 is also secured to this rod. When the case 4 is moved to the position shown in Fig. 2 it turns the actuating arm 26 which turns the arm 23 to raise the valve 20 to the closed position shown. Upon withdrawal of the case 40 the valve due to its own weight falls to the position shown in Fig. 1 which allows

the water to pass from the upper tank 14 into the lower tank 13. The downward movement of the valve 20 turns the arm 26 upwardly in position to be depressed by the 5 next case of bottles moved into the bottle washing machine. An actuating arm 27 shown in Fig. 1 also extends into the path of movement of the bottle cases. This arm 27 is pivotally connected to an arm 28 which is 10 pivotally mounted at its lower end on a bracket 29 secured to the frame of the machine. As the case is moved into the hood 5 as shown in Fig. 3 it engages the actuating arms 26 and 27 and as it is moved further 15 into the machine it turns the arm 26 to close the valve 20 and the actuating arm 27 turns the arm 28 on its pivot as shown in Fig. 2. An arm 30 is pivotally mounted on a bracket 31 secured to the steam valve 11 and 20 the opposite end of the arm 30 is pivoted on the pivot 32 for the arm 27. As the arm 27 is moved to the left of Fig. 2 the arm 30 is turned on its pivot 31 causing the end 33 of the arm 30 to depress the stem 34 of the 25 steam valve 11 and thus open the steam valve. At this time the steam passes through the ejector 12 which carries the water from the lower tank 13 with the steam, the water being thus heated by the steam and sprayed 30 into the bottles are hereinbefore described in order to wash the bottles. This washing operation continues until all of the water from the lower tank 13 is discharged at which time steam flows thru the pipe 17 with 35 which the small quantity of water discharging into the ejector from the pipe 18 providing saturated steam for sterilizing. When the sterilizing process is completed the operator draws the handle 35 to the right 40 of Fig. 3 which turns the arm 28 on its pivot and causes the arm 27 to eject the case 4 containing the bottles from the hood and at the same time the movement of the arm 28 turns the arm 30 to allow the steam valve 45 11 to close. As the case is withdrawn by hand from this point the weighted valve 20 drops to the position shown in Fig. 1 allowing the accumulated wash water in the upper tank 14 to pass into the lower tank 13. 50 an overflow 36 being provided to carry off any excess water. As a new case is moved into the machine the valve 20 is again closed by turning of the actuating arm 26 and the subsequent movement of the arm 27 again 55 opens the steam valve 11 to allow the rinsing and sterilizing operation to repeat. It will thus be seen that it is only necessary for the operator to move the cases containing the bottles into the machine and to eject the 60 cases from the machine by pulling the handle 35, the operations of washing and sterilizing the bottles being entirely automatic.

It is evident from the foregoing that a particular feature of this invention is in the 65 provision of a tank 14 in which the rinse

water discharged from the header 8 accumulates during the rinsing operation, and that, upon completion of the rinsing operation and removal of the bottle case from position over the header, the accumulated rinse water 70 is discharged to the tank 13 which has an outlet to the ejector 12. This arrangement first traps the hot rinse water for use in a subsequent rinsing operation and thus the hot water in the tank 13 when discharged 75 with steam through the header has a much higher temperature than would be the case were cold water used as in previous devices of this character.

It is further to be noted that a feature of 80 this invention is in providing apparatus including an ejector operating to withdraw hot water from a tank and discharge it through a spray head. Steam ejectors in general are adapted to discharge cold water commingled with the steam for the reason that the cold water continuously causes condensation of steam in the ejector resulting in partial vacuum which draws the water into the ejector. We have devised an arrangement 85 of parts whereby water having a temperature as high as 180 degrees will be caused to flow readily through the ejector. This is accomplished by the provision of the cold water pipe 18 discharging into the outlet of 90 the second tank containing the hot rinse water. This tank, as heretofore described, is provided with an overflow 36 in order that a predetermined volume of water is always 95 in readiness for the rinsing and sterilizing operation. With the cold water discharging into the outlet continuously in small quantity, the ejector 12 is cooled so that, on the opening of the steam valve and flow 100 of steam into the ejector, condensation will take place and the ejector will function to draw the comparatively hot water from the tank 13. The quantity of water flowing through the pipe 18 is small and has a double 105 purpose—that is, not only to cool the ejector by discharging the water into the outlet line of the tank 13 but to also replenish the rinse water. By this is meant that the rinse water is kept fairly clear by continual introduction of fresh clear water thereinto causing 110 discharge of water from the tank 13 through the overflow 36. Thus approximately as rapidly as the water deteriorates through the rinsing operation, fresh water is supplied. This result is possible due to the fact that 115 the bottles have been washed previous to the rinsing operation and therefore the greater part of the deleterious matter has been removed and the contamination of the water through the rinsing operation is comparatively slight. Therefore the flow of cold water through the pipe 18 need only be small 120 in volume per unit of time to maintain the rinse water approximately clear.

From the foregoing description it becomes 125 130

evident that the device is very simple and efficient in operation, will not easily get out of order, is practically automatic in operation, and provides a device which accomplishes the objects described.

Having thus fully described our invention, its utility and mode of operation, what we claim and desire to secure by Letters Patent of the United States is—

- 10 1. In a bottle washing machine, an upper reservoir, a lower reservoir adapted to contain a definite amount of water, a track over the upper reservoir by means of which a case containing bottles in inverted position may be moved over the upper reservoir, a spray head having a multiplicity of jets corresponding to the number of bottles in the case and adapted to discharge into the bottles, a steam operated ejector adapted to withdraw the water from the lower reservoir and discharge it through the jets of the spray head, a valve for controlling flow of steam to the ejector, a control member for the said valve adapted to be actuated by the case to open the valve as the case is moved into position over the spray head, the upper reservoir providing a receptacle for the water falling from the bottles and having an outlet discharging into the lower reservoir, a valve controlling the said outlet and an actuating member for the said valve adapted to be engaged by the bottle case, the arrangement being such that as the case is moved to position over the spray head the steam valve is opened and the outlet valve is closed and upon withdrawal of the case the outlet valve is opened.

20 2. In a bottle washing machine, an upper reservoir, a lower reservoir adapted to contain a definite amount of water, a steam operated ejector adapted to withdraw water from the lower reservoir, a spray head over the upper reservoir having a multiplicity of jets through which the water is discharged from the lower reservoir by the ejector, a case containing a series of bottles in inverted position adapted to be positioned over the spray head with the mouths of the bottles registering over the jets, a valve controlling flow of steam through the ejector, an actuating member for opening the said valve operated by the positioning of the case over the spray head, the upper reservoir providing a receptacle for the water falling from the bottles and having an outlet discharging into the lower reservoir, a valve controlling the said outlet, an actuating member for the said valve adapted to be operated by positioning the case over the spray head to close the valve, the valve being adapted to automatically open upon removal of the case.

30 3. In a bottle washing machine, an upper reservoir, a lower reservoir adapted to contain a definite amount of water, a track over the upper reservoir by means of which a case containing bottles in inverted position may be moved over the upper reservoir, a spray head having a multiplicity of jets corresponding to the number of bottles in the case and adapted to discharge into the bottles, a steam operated ejector adapted to withdraw the water from the lower reservoir and discharge it through the spray head into the bottles, the water from the spray head and bottles falling into the upper reservoir, the arrangement being such that removal of the case from the spray head disengages the actuating member to allow the said valve to open and allow the water to return from the upper to the lower reservoir.

40 4. In a bottle washing machine, an upper reservoir, a lower reservoir adapted to contain a definite amount of water, the upper reservoir having an outlet discharging into the lower reservoir, a valve controlling the said outlet, an actuating member for the said valve, a spray head, a case containing bottles in inverted position adapted to position over the spray head engaging the actuating member to close the said valve, a steam ejector adapted to withdraw the water from the lower reservoir and discharge it through the spray head into the bottles, the water from the spray head and bottles falling into the upper reservoir, the arrangement being such that removal of the case from the spray head disengages the actuating member to allow the said valve to open and allow the water to return from the upper to the lower reservoir.

50 5. In a bottle washing machine, an upper reservoir, a lower reservoir adapted to contain a definite amount of water, guide means over the upper tank by means of which a case containing bottles may be moved thereover, a spray head having a multiplicity of jets corresponding to the number of bottles in the case, the case being adapted to be positioned on the guide means with the bottles in inverted position over the jets, a steam operated ejector adapted to withdraw the water from the lower reservoir and discharge it through the jets of the spray head, the upper reservoir providing a receptacle for the water falling from the bottles and having an outlet discharging into the lower reservoir, and a valve controlling the said outlet adapted to be closed by movement of the case over the spray head and opened by withdrawal of the case therefrom.

60 6. In a bottle washing machine, an upper reservoir, a lower reservoir adapted to contain a definite amount of water, the upper reservoir having an outlet discharging into the lower reservoir, a spray head, a steam operated ejector adapted to withdraw the water from the lower reservoir and discharge it through the spray head into the bottles, the water from the spray head and bottles falling into the upper reservoir, the arrangement being such that removal of the case from the spray head disengages the actuating member to allow the said valve to open and allow the water to return from the upper to the lower reservoir.

water from the lower reservoir and discharge it through the spray head, a cold water pipe adapted to constantly discharge a small stream of cold water into the ejector, 5 a case containing bottles in inverted position adapted to be positioned over the spray head, the upper reservoir providing a receptacle for the water discharged from the spray head, a valve controlling flow through 10 the outlet in the upper reservoir, and means for closing the valve actuated by the case in positioning the same over the spray head.

7. In a bottle washing machine, an upper reservoir, a lower reservoir adapted to contain a definite amount of water, the upper reservoir having an outlet discharging into the lower reservoir, a spray head, a steam operated ejector adapted to withdraw the water from the lower reservoir and discharge it through the spray head, a case containing bottles in inverted position adapted to be positioned over the spray head, the upper reservoir providing a receptacle for the discharged water from the spray 25 head, a valve controlling flow through the outlet of the upper reservoir, and valve operating means for closing the valve actuated by positioning the case over the spray head, the valve being adapted to automatically 30 open upon removal of the case.

8. In apparatus of the character described, a rinsing and sterilizing header, means for supporting a case of bottles thereover, a tank surrounding the header and into which 35 rinse water discharged from the header accumulates, a second tank, there being an aperture in the wall of the first tank opening into the second tank through which rinse water may be discharged from the first to 40 the second tank, means for closing the said aperture whereby the rinse water is retained in the first tank, a steam line for the said header, an ejector in the said line, an outlet for the second tank leading to the ejector, 45 a cold water supply conduit discharging into the said second tank outlet wherein cold water in a limited quantity is caused to flow into the ejector, an overflow for the said second tank whereby the volume of water 50 contained in the second tank is limited in quantity, a valve in the steam line through opening of which the ejector operates to withdraw the water from the second tank and discharge it into the header and then 55 steam only flows to the header, and means for opening the valve in the first tank outlet through removal of the bottle case from position over the header.

9. In apparatus of the character described, 60 a rinse water and steam header, means for supporting a case of bottles thereover, a tank into which the rinse water discharges through the header accumulates, a second tank, there being an outlet from the first 65 tank into the second tank, a valve controlling

the same, a steam line for the header, an ejector in the line, an outlet for the second tank discharging into the ejector, an overflow for the second tank whereby only a limited quantity of water may be maintained 70 in the second tank, a cold water line leading into the second tank whereby the ejector is cooled through continual flow of cold water thereto in a limited quantity and between operations of the header tends to accumulate in the second tank and thereby maintains the rinse water therein approximately clear, a valve in the steam line, the passing of steam through the ejector operating to withdraw the water from the second tank discharging the same commingled with steam through the header and, upon exhaustion of supply of the tank, steam and a negligible quantity is discharged through 75 the header for sterilizing the bottles subsequent to the rinsing operation.

10. In a machine for washing bottles and the like, a spray head over which a case containing articles to be washed may be positioned, a receptacle into which the wash water discharged through the spray head may be accumulated, a second receptacle into which the accumulated water of the first receptacle may be discharged, a steam line, a steam operated ejector in the steam line adapted to withdraw water from the second reservoir and discharge it through the spray head and to eject steam through the spray head upon exhaustion of the water supply of the second reservoir, means controlled by the positioning of the case over the spray head for opening the steam line to the ejector and to automatically close the same through withdrawal of the case from washing position, and means operated by the positioning of the case over the spray head to prevent flow of water from the first to the second reservoir and to permit such flow upon removal of the bottle case.

11. In a machine for washing bottles and the like, a spray head over which a case containing articles to be washed may be positioned, a receptacle into which the wash water discharged through the spray head may be accumulated, a second receptacle into which the accumulated water of the first receptacle may be discharged, a steam line, a steam operated ejector in the steam line adapted upon flow of the steam thereinto to withdraw the water from the second receptacle and discharge the same through the spray head and to eject steam to the spray head upon exhaustion of the water in the second reservoir, a cold water supply providing for a continual flow of cold water into the ejector in quantity per unit of time less than the inlet capacity of the ejector, an overflow pipe in the second receptacle whereby a predetermined quantity of the water may be retained in the second receptacle and

whereby the continual flow of the cold water to the ejector causes continual flow of contaminated wash water from the surface of the water in the second receptacle, means actuated by the positioning of a case over the spray head to open the steam line and thereby cause operation of the ejector and withdrawal of the accumulated water of the second receptacle to discharge through the spray head, and means operated by the positioning of a case over the spray head to retain the water discharged through the spray head in the first receptacle, said means operating upon withdrawal of the case to cause the accumulated water of the first receptacle to discharge to the second receptacle. ¹⁵
